UNITED STATES PATENT OFFICE.

WILLIAM E. PENN AND CHARLES S. BROWN, OF LAKE MILLS, WISCONSIN,
ASSIGNORS TO THE F. B. FARGO & COMPANY, OF SAME PLACE.

CHURN AND BUTTER-WORKER.

SPECIFICATION forming part of Letters Patent No. 604,262, dated May 17, 1898.

Application filed November 5, 1897. Serial No. 657,476. (No model.)

To all whom it may concern:

Be it known that we, WILLIAM E. PENN and CHARLES S. BROWN, of Lake Mills, in the county of Jefferson and State of Wisconsin, have invented a new and useful Improvement 5 in Churns and Butter-Workers, of which the following is a description, reference being had to the accompanying drawings, which are a part of this specification.

10 Our invention relates to that class of churns and butter-workers in which a revolving drum and butter-working rolls therein are employed both for churning and working butter in the same receptacle and by the same devices, the 15 two operations being practically a continuous one; and the invention is directed to simplifying and improving the construction of the receptacle and devices therein and mounted directly thereon for churning and working 20 butter and to improved practical and suitable means for properly and readily operating the receptacle and related devices.

The invention consists of the mechanism and devices, their parts and combinations of 25 parts, as hereinafter described and claimed, or their equivalents.

In the drawings, Figure 1 is an elevation of the front end of the machine. Fig. 2 is a side elevation of the machine. Fig. 3 is a top plan 30 view of the machine, the drum being shown in section to exhibit interior parts. Fig. 4 is a transverse section of the drum centrally. Fig. 5 is an elevation of parts of the driving and operating mechanism, the view being 35 from the inner or drum side of the mechanism, looking away from the drum. Figs. 6, 7, 8, and 9 are details of the construction.

In the drawings, A is a frame of suitable 40 size and form for supporting the operative parts. The receptacle 10, which we have shown as a cylindrical drum, though a rectilinear box or other form of receptacle may be used, is mounted revolubly on the frame, conveniently by the shaft or arbor 11 at the front 45 end and the arbor 11' at the rear end. The arbor 11 is at its inner end provided with or fixed in a branching flange or spider 12, which is footed against and is secured to the drum-head. The arbors 11 11' are journaled on the 50 frame. The drum is provided with a door 13

and preferably with a glazed peep-hole 14. In the drum there are one or more strips 15 15, fixed in the drumheads and serving as dashers and buckets adapted for dashing against the cream during churning and for 55 elevating the butter by the rotation of the drum during butter-working, and also may serve to elevate and support the butter in convenient position for removing it from the drum after it has been worked through the 60 door 13. One or more bars 16, fixed to the drumheads, may be used for additionally agitating the cream while churning and as complementary sides to the shelves 15 for forming a hopper-like construction for directing 65 the butter onto the rolls; also, there is a set of butter-working rolls 17 17 near to each other and parallel with and on diverse sides of the axis of the drum, mounted revolubly in the heads of the drum, the journals of which rolls 70 18 18, that mesh with each other under the spider or between the spider and the head of the drum, as clearly indicated in Fig. 7. When 75 used as a butter-worker, these rolls revolve inwardly toward each other on that side temporarily at the top, being actuated by means hereinafter described.

For revolving the drum with a constant and 80 moderately-rapid motion for churning the arbor 11 is provided with a spur-wheel 19, that meshes with a spur-wheel 20, splined on the driving-shaft 21. This shaft is provided with a belt-pulley 22.

85 While working butter the drum is rotated a half-revolution intermittently to elevate the butter and drop it on the rolls 17, which work the butter by pressure as it passes downwardly between them by their inward revolution. For rotating the drum intermittently the wheel 20 is shifted along on shaft 21 out of mesh with wheel 19 and into clutch with a sprocket-wheel 23, revolubly loose on shaft 21, which wheel 23 carries a belt or sprocket-chain 24, running thence on and partially about wheel 25, loose on arbor 11, and between disks 26 26, fixed on arbor 11 near to and on each side of the wheel 25, and thence running about an idle-wheel 27, mounted adjustably 90 95 100

on a bracket 28, fixed on the frame, and about another idle-wheel 29, mounted on a stud or pin fixed in the weight-actuated lever 48, pivoted on the frame. The axle-pin 30 of wheel 27 is adjustable in a slot in bracket 28, being held thereto releasably by a nut, whereby the path of the sprocket-chain or belt on and about the wheel 25 may be regulated. The chain belt 24 is provided with a dog or catch 31, which may consist of a short bar secured transversely thereof to the belt 24 and which extends beyond the sides of the belt and is adapted to and does enter recesses 31' 31" (of which there are two diametrically opposite sets) in the disks 26 as it comes opposite thereto, and thereby engages the disks, causing them and the drum 10 to rotate a half-revolution at each engagement of the dog with said disks, while the belt travels forward continuously. The length of the belt is such that the dog engages and rotates the disks 26 only after such intervals of time as shall have permitted in the meantime the sufficient operation of the rolls 17 for working the supply of butter in the drum past them.

For revolving the rolls 17 during the butter-working process a spur-wheel 32, splined on the driving-shaft 21, is shifted on the shaft into the plane of the roll-journal gear-wheels 18 concurrently with the shifting of the driving-wheel 20 into clutch with the sprocket-wheel 23, whereby the spur-wheel 32 meshes alternately first with one and then with the other gear-wheel 18 as these gear-wheels are brought thereto by the intermittent and periodic half-revolution of the drum. This shifting of the wheels 20 and 32 concurrently respectively into clutch with sprocket-wheel 23 and gear-wheel 18 is readily accomplished by a shifting bar 33, mounted reciprocally in brackets 34 34 on the frame, the lateral turned ends of the shifting bar being furcate and straddling and riding in grooves therefor, respectively, in the hubs of wheels 20 and 32. A shifting lever 35, pivoted on the frame and to the bar 33, is adapted for shifting the bar 33 and thereby throwing the wheels 20 and 32 into and out of clutch and mesh, as described. A drop-latch 36, pivoted on the lever 35, engages a bracket 34 (serving as a catch) and locks the bar 33 in position and the wheels 20 and 32 to their work.

For locking the disks 26 and thereby the drum intermittently against rotation during the operation of working the butter a lever-latch 37, Fig. 5, pivoted medially on the frame, is provided with a notch 38, adapted to receive the pins 39 on a disk 26, severally, being held releasably thereto by the spring 40, whereby the latch 37 is so in engagement with one of said pins 39 that the disk 26 is held against rotation; but the latch 37 is provided with an arm 37', which is arranged to be temporarily engaged at its upper end by the chain-carried dog 31 and be pushed down, thereby carrying that end of the latch 37 away from the pin 39, while at the same time the

traveling chain 24, by means of the dog 31, rotates the disk 26, moving the pin 39 away from the recess 38. The dog 31 as it goes down remains in contact with the overturned end of arm 37' only a brief time, and then the dog slips off the end of the arm and leaves the latch 37, actuated by the springs 40, to engage the succeeding pin 39 as it comes to the recess 38, thus stopping the rotation of the drum when it has revolved a half-revolution. A bent lever 41 is pivoted near one extremity on the frame and carries an idle-wheel 42, mounted thereon by a stud-pin. The forward end of the lever 41 is arranged to be contacted along the under edge thereof by the pins 39 severally and thereby lifted to such extent and at such time as to hold the idler 42 against and thereby to lift the chain 24 near the disks 26 26 temporarily when approaching the close of each half-revolution of the disks, thereby holding the dog 31 on the moving chain in the recesses 31' and in engagement with the disks 26 until the drum 90 has completed its half-revolution, when the lever 41 drops off the moving pin 39, permitting the chain to fall slightly away from the wheel 25 and sufficiently far to instantly release the dog 31 from engagement with the disks 26 and at the same moment that the other pin 39 comes opposite and enters the recess 38 in the latch 37, thus locking the drum against further revolution until the latch 37 shall be again released from the disk 100 by the succeeding pin 39 pushing down the latch. The idler-carrying lever 41 is provided at its rear end with an inclined or beveled cam 43, so disposed as to engage a pin 44, fixed in the shifting bar 33, and cause the forward end of the lever 41 to be lifted out of the path of the pins 39 when the gear is put in position for revolving the drum for churning.

During a portion of the butter-working operation, while the drum is revolving on its axis, the gear-wheel 32 is not in mesh with either of the wheels 18, being outside their path, and when a wheel 18 comes to the wheel 32, if the ends of opposing teeth should contact, there would be blocking or breaking of the parts, except some part yields, until the complementary teeth and spaces come properly into mesh. To provide for this contingency the driving-shaft 21 at its inner end is mounted in a box 45, that is slidable endwise on the frame, the box and shaft being held yieldingly up to their work by a weighted lever 46, Fig. 8, pivoted in the frame. The box 47, in which the other end of shaft 21 is mounted, is pivoted at one end and has a little play at the other end to provide for this possible slight shifting of the shaft. The furcate ends of the shifting bar 33 are sufficiently loose on the hubs of wheels 20 and 32 to also permit of this movement.

What we claim as our invention is—

1. The combination with a revoluble drum and rolls therein parallel with the axis of the

drum the journals of which rolls extend through the drum and have gears thereon, of means for rotating the drum partial revolutions intermittently, and means therewith for 5 rotating the rolls on their axes in the periods of non-movement of the drum.

2. The combination with a revoluble drum and rolls therein parallel with its axis said rolls having journals extending through the 10 drum and provided with gears thereon, of a driving-shaft provided with a gear-wheel eccentric to the axis of the drum disposed to mesh alternately with the gear-wheels on the several rolls and rotate them when by the 15 rotation of the drum it is in a line with the axis of the drum and the axis of the roll, and means for revolving the drum.

3. The combination with a revoluble drum, of a loose pulley on the arbor of the drum, a 20 disk or disks fixed on the arbor alongside the loose pulley, and a traveling belt or chain running on and partially around the arbor loose pulley, the belt or chain being provided with a dog or catch adapted to engage the 25 disk or disks and rotate the arbor a partial revolution before release therefrom.

4. The combination with a revoluble drum provided with an axial arbor, of a loose pulley thereon, disks of greater diameter than 30 the loose pulley alongside of the loose pulley fixed on the arbor, and a belt or chain traveling on the pulley between the disks and provided with a dog adapted intermittently to drop into recesses in the disks and rotate 35 the arbor a partial revolution and then to be released therefrom.

5. The combination with a revoluble drum provided with an axial arbor, of a loose pulley thereon, a disk or disks alongside the loose 40 pulley fixed on the arbor, a belt or chain traveling continuously on and partially around the loose pulley, a dog on the belt or chain adapted to engage the disk or disks intermittently and rotate the arbor a partial revolution, and a lever on which an idler is 45 mounted, the lever being disposed to be lifted by contact with an eccentric-pin on said disk and thereby to force the idler against and raise the belt or chain holding the dog in engagement with the disk briefly and then by 50 the release of the lever from the eccentric allowing the lever and idler to drop and the dog to suddenly escape from the disk or disks.

6. The combination with a revoluble drum 55 having a fixed arbor, of a loose pulley on the arbor, a disk or disks fixed on the arbor alongside the loose pulley, a belt or chain running continuously on and partially around the loose pulley, a dog on the belt or chain adapted 60 intermittently to engage the disk or disks and rotate the arbor a partial revolution, and a spring-actuated lever adapted to engage said disk and hold the same against rotation when it is not being moved by said belt or chain.

65 7. The combination with a revoluble drum having a fixed arbor, of a loose pulley on the

arbor, a disk or disks fixed on the arbor alongside the loose pulley, a belt or chain running continuously on and partially around the loose pulley, a dog on the belt or chain adapted intermittently to engage the disk or disks and rotate the arbor a partial revolution, and an 70 arm on the lever disposed to be engaged briefly by the dog on the belt or chain whereby by the movement of the belt or chain the lever 75 is released from engagement with the disk and the arbor is permitted to rotate.

8. The combination with a revoluble drum having a fixed arbor, and rolls in the drum parallel with its axis said rolls having gear-wheels outside of the drum intermeshing with each other in the line of the axis of the drum, of a driving-shaft, a gear-wheel splined on the driving-shaft adapted to be shifted into and out of the plane of the roller gear-wheels and 80 in position to mesh with each of said gear-wheels when adjacent to and in or near the line of the axis of said gear-wheel and the axis of the drum, and a driving gear-wheel splined on the driving-shaft adapted to mesh 85 with a gear-wheel on the drum-arbor for rotating the drum continuously and to be shifted into clutch with a belt or chain carrying wheel for rotating the drum intermittently.

9. The combination with a revoluble drum 90 having a fixed arbor, and rolls in the drum parallel with its axis, said rolls having gear-wheels outside of the drum intermeshing with each other in the line of the axis of the drum, of a driving-shaft, a gear-wheel 95 32 splined on the driving-shaft adapted to be shifted into and out of the plane of the roller gear-wheels and in position to mesh with each of said gear-wheels when adjacent to it in or near the prolonged line of the axis of said gear-wheel 100 and the axis of the drum, a wheel 20 splined on the driving-shaft adapted when in action to rotate the drum, a wheel on the drum-arbor so disposed as on occasion to mesh with the wheel 20 on the driving-shaft, and a shifting bar 105 slidable on the frame adapted concurrently to shift the drum-driving wheel and the roll-driving wheel.

10. In combination with a driven revoluble 110 drum and a pair of roll-journal gears thereon intermeshing in the line of the axis of the drum, of a driving-shaft having a gear thereon adapted intermittently to mesh with said roll-journal gears, and a sliding weight-controlling box in which the driving-shaft is 115 mounted at one end, provided for a yielding of the parts in case of a mismeshing contact of a roll-gear and the driving-gear.

11. In an automatic gear-controlling device, the combination of a revoluble disk provided 120 with an eccentric-pin, an idler-carrying lever 41 adapted intermittently to be lifted by contact with the pin on the revolving disk, a cam 43 on the lever, and a bar 33 provided with a pin 44 adapted when the bar is shifted in one 125 direction to engage the cam and lift the lever out of the path of the pin on the disk.

12. In a combined churn and butter-worker, the combination with a revoluble drum, of two butter-working rolls in the drum parallel with but on different sides of and adjacent to its axis, two sets of hopper-like strips, the sets of strips being on opposite sides of the rolls, and means for rotating the drum a partial revolution intermittently.

In testimony whereof we affix our signatures in presence of two witnesses.
